United States Patent [19]

Stillwagon

US00D351278S
[11] Patent Number: Des. 351,278
[45] Date of Patent: ** Oct. 11, 1994

- [54] COMBINATION KEY RING AND REMOTE CONTROL SWITCH
- [75] Inventor: Woodrow C. stillwagon, Atlanta, Ga.
- [73] Assignee: Stillwagon Applied Technology, Inc., Columbus, Ohio
- [**] Term: 14 Years
- [21] Appl. No.: 727,136
- [22] Filed: Jul. 9, 1991
- [52] U.S. Cl. D3/208
- [58] Field of Search ..... D3/207-212; 70/456 R, 456 B; D14/218; D13/168

[57] CLAIM

The ornamental design for a combination key ring and remote control switch, as shown and described.

DESCRIPTION

FIG. 1 is a perspective view of a combination key ring and remote control switch showing my new design, in accordance with a first embodiment of the present invention;

FIG. 2 is a front view thereof;

FIG. 3 is a left side view thereof;

FIG. 4 is a right side view thereof;

FIG. 5 is a rear view thereof;

FIG. 6 is a top view thereof;

FIG. 7 is a bottom view thereof;

FIG. 8 is a perspective view of a combination key ring and remote control switch showing my new design, in accordance with a second embodiment of the present invention;

FIG. 9 is a front view thereof;

FIG. 10 is a right side view thereof;

FIG. 11 is a left side view thereof;

FIG. 12 is a rear view thereof;

FIG. 13 is a top view thereof; and,

FIG. 14 is a bottom view thereof.
